UNITED STATES PATENT OFFICE

104,916

DESIGN FOR A CLOCK FACE

Lee A. Du Rocher, Norco, La.

Application August 21, 1936, Serial No. 64,514

Term of patent 14 years

To all whom it may concern:

Be it known that I, Lee A. Du Rocher, a citizen of the United States of America, residing at Norco, county of Saint Charles, and State of Louisiana, have invented a new, original, and ornamental Design for a Clock Face, of which the following is a specification, reference being had to the accompanying drawing forming part thereof, wherein:

Figure 1 is a front elevation of a clock face, showing my new design.

Figure 2 is an edge view.

I claim:—

The ornamental design for a clock face, as shown.

LEE A. DU ROCHER.
